(57) **CLAIM**

We claim the ornamental design for a support mount for mounting luminaire assembly, as substantially shown and described.

DESCRIPTION

FIG. 1 is a top perspective view of a support mount coupled with a luminaire assembly in accordance with the present design. The broken lines depict portions of the support mount coupled with the luminaire assembly that form no part of the claimed design.

FIG. 2 is a bottom perspective view of the support mount coupled with the luminaire assembly shown in FIG. 1. The broken lines depict portions of the support mount coupled with the luminaire assembly that form no part of the claimed design.

FIG. 3 is a top view of the support mount coupled with the luminaire assembly shown in FIG. 1. The broken lines depict portions of the support coupled with the luminaire assembly that form no part of the claimed design.

FIG. 4 is a bottom view of the support mount coupled with the luminaire assembly shown in FIG. 1. The broken lines depict portions of the support mount coupled with the luminaire assembly that form no part of the claimed design.

FIG. 5 is a left view of the support mount coupled with the luminaire assembly shown in FIG. 1. The broken lines depict portions of the support mount coupled with the luminaire assembly that form no part of the claimed design.

FIG. 6 is a right view of the support mount coupled with the luminaire assembly shown in FIG. 1. The broken lines depict portions of the support mount coupled with the luminaire assembly that form no part of the claimed design.

FIG. 7 is a front view of the support mount coupled with the luminaire assembly shown in FIG. 1. The broken lines depict
